United States Patent Office.

WILLIAM R. SMITH, OF BRANFORD, CONNECTICUT.

Letters Patent No. 101,673, dated April 5, 1870.

IMPROVEMENT IN REVERSIBLE LATCHES.

The Schedule referred to in these Letters Patent and making part of the same.

To all whom it may concern:

Be it known that I, WILLIAM R. SMITH, of Branford, in the county of New Haven and State of Connecticut, have invented a new Improvement in Reversible Latches; and I do hereby declare the following, when taken in connection with the accompanying drawings and the letters of reference marked thereon, to be a full, clear, and exact description of the same, and which said drawings constitute part of this specification, and represent in—

Figure 1 a side view of the upper portion of the latch-case;

Figure 2, the same, with the plate removed; and in Figure 3, a section on line $z z$, looking toward the face-plate.

This invention relates to an improvement in knob-latches, the object being the construction of the latch and its operative mechanism, so that the latch-bolt may be reversed to serve for either a right or left-hand door; and

The invention consists in combining with the lever upon which the follower operates, and to which the latch-bolt is pivoted, a second lever, to which the first is pivoted, and so that by the movement of the second the lever may be dropped out of its proper position, and so that when dropped the latch-bolt may be detached therefrom, reversed, and replaced, and the lever, returning to its fixed position, the latch-bolt is prevented from removal therefrom.

A is the latch-case.

B, the hub or follower.

C, the latch-bolt, the said latch-bolt pivoted to a lever, D, in the usual manner, and the said lever D hung in such relative position to the follower B that,

by turning the follower B, the bolt is drawn into the case in the usual manner.

The latch-bolt is attached to the lever by a pivot, *d*, and is prevented from removal therefrom by a lug, *f*, see fig. 3, formed on one side of the case, and resting upon a projection, *h*, on the tail of the latch-bolt.

Instead of fixing the pivot *a* in the case, I form it upon one arm E of a lever, the said lever pivoted at *n*, and the other arm F extending along the inside of the case with a projection, *r*, extending through a slot, I, in the case, as seen in fig. 1.

Therefore, when the arm F of the said lever is raised, as seen in broken lines fig. 2, the lever D will be dropped, carrying with it the latch-bolt C, as seen in broken lines fig. 2, in which position the projection *h* is carried from under the lug *f* on the case, so that by taking hold of the latch-bolt on its outer end it may be taken from the pivot, withdrawn, turned to the desired position, replaced, and the lever E F left free will return the lever D and latch-bolt to the first position by means of the spring S, see fig. 2, the said spring bearing under a projecting arm of the lever D, the same spring serving to force the bolt forward when it has been drawn in in the usual manner.

I claim as my invention—

The lever E F pivoted within the case, combined with the lever D, and the latch-bolt C, all pivoted together and operating to throw the latch-bolt away from the lug *f*, substantially as and for the purpose specified.

W. R. SMITH.
